HENRY A. OWEN, OF WHITINSVILLE, MASSACHUSETTS, ASSIGNOR TO THE WHITIN MACHINE WORKS, INCORPORATED, OF WHITINSVILLE, MASSACHUSETTS.

WARP STOP-MOTION FOR LOOMS.

SPECIFICATION forming part of Letters Patent No. 729,960, dated June 2, 1903.

Application filed May 8, 1901. Serial No. 59,262. (No model.)

To all whom it may concern:

Be it known that I, HENRY A. OWEN, a citizen of the United States, residing at Whitinsville, in the county of Worcester and State 55 of Massachusetts, have invented a new and useful Improvement in Warp Stop-Motions for Looms, of which the following is a specification.

This invention has reference to an improvement 10 in the class of automatic loom stop mechanism in which detector-plates are supported by the warp-threads above a series of saw-tooth plates, to one or more of which is imparted a reciprocating motion transversely 15 to the warp-threads.

The invention consists in the peculiar and novel construction of the mechanism and the combination of the parts whereby the reciprocating blades are operated and the loom is 20 stopped, as will be more fully set forth hereinafter.

Figure 1 is an end view of such parts of a loom as are required to illustrate the invention. Fig. 2 is a view of the end frames and 25 parts of the loom, illustrating the invention. Fig. 3 is a top view of the saw-blade stop-motion. In Figs. 2 and 3 the central portions are omitted for the purpose of reducing the size of the drawings and showing the essential 30 parts on a larger scale.

Similar marks of reference indicate corresponding parts in all the figures.

In the drawings, A indicates the end frames of the loom; B, the lay; C, the warp-beam, 35 and D a warp stop-motion in which a saw-blade is reciprocated between two stationary saw-blades. In the preferred form, as shown in the drawings, a movable saw-blade d is placed between a pair of fixed saw-blades d' 40 d', the arrangement being duplicated. The ends of the two saw-blades d d are secured by connecting-bars d²⁰ and d²¹, so that both the saw-blades may be reciprocated together. Two sets of detector-plates d² are suspended 45 from the warp-threads c. When a warp-thread breaks, the detector-plate suspended on the same drops on the saw-blades and locks the reciprocating saw-blade against movement in one direction.

To one end of the saw-blade d or in the preferred form to the bars d²⁰, connecting

the ends of the saw-blades d d, I secure a wire, rope, cord, or chain d³ and passing the same over the sheave d⁴ secure the other end to one end of the coiled tension-spring d⁵, the other end of which is secured to the end frame A. In place of the coiled tension-spring d⁵ a weight may be used, if desired. To the opposite end of the saw-blades d d or in the preferred form to the bar d²¹ the rope 60 d³⁰ is secured and passed over a sheave d³⁰, from which it passes downward over the sheave d⁶ to the lever d⁷, to which it is secured. The lever d⁷ is pivoted on the sword b near the lay and forms, with the overweighted 65 pawl d⁸, a bell-crank lever pivoted on the lay-sword b. The stop d⁹ on the lower part of the lay-sword holds the lever d⁷ against the strain exerted by the tension-spring d⁵ on the saw-blades d d and the ropes d³ d³⁰. 70

The stop-rod d¹⁰ is supported at the front end on a stud d¹⁵ or other support, on which it may slide, and is connected with the usual shipper-lever a. The stop-rod may, however, connect with any other mechanism by which the 75 loom may be stopped. The stop-rod d¹⁰ rests near its inner end on the support d¹¹, on which it may slide. A shoulder d¹⁶ on the stop-rod d¹⁰ is placed so that when the lay approaches the end of its rearward oscillation the pawl 80 d⁸ may engage with the shoulder and move the stop-rod backward to operate the arm a to disengage the spring shipper-lever or operate a stop or knock-off motion to stop the loom. 85

During the normal operation of the loom the swing of the lay and the lay-sword causes the stop d⁹ to carry the lower end of the lever d⁷ forward. This movement is transmitted by the rope d³ to the saw-blades d d and exerts a strain on the tension-spring d⁵ or, if desired, on a weight. On the backward movement of the lay the tension spring or weight, acting on the rope d³ and the saw-blades d d, holds the lower end of the lever d⁷ against the stop d⁹. When now a warp-thread breaks and one of the detector-plates d² drops on a set of the saw-blades during the forward movement of the lay, the saw-blade d, the teeth of which are beveled in the opposite direction to the teeth of the fixed saw-blades d' d', is drawn forward, the detector-plate riding 90 95 100

on the bevels of the teeth until the saw-blade d has been drawn fully forward by the movement of the lay. As soon as the lay commences to swing backward the tension-spring 5 d^5 draws the saw-blade d backward. The detector-plate enters between the vertical edges of the fixed saw-blades $d' d'$ and the vertical edges of a tooth on the saw-blade d , thereby locking the same and releasing the tension 10 on the rope or cord connecting the saw-blades $d d$ with the lever d^7 . The weighted pawl d^8 now acts to swing the lever into the position shown in broken lines in Fig. 1 and engages with the shoulder on the stop-rod d^{10} . Drawing 15 the same backward it acts on the mechanism to release the spring shipper-lever and stop the loom.

The warp stop-motion and operating mechanism may be readily attached to any existing loom.

Having thus described my invention, I claim as new and desire to secure by Letters Patent—

1. In a warp stop-motion for looms, two fixed 25 members, a reciprocating member, means for moving the reciprocating member in one direction, a lever provided with an overbalanced pawl carried by the lay, flexible connection between the lever and the reciprocating member for moving the member in the opposite direction, a detector-plate, and means engaged by the pawl for knocking off the loom when the detector-plate arrests the reciprocating member, as described.
2. In a warp stop-motion for looms, the combination with detector-plates supported on the warp-threads, the fixed saw-blades and a reciprocating saw-blade, of a tension-spring connected with one end of the reciprocating 40 saw-blade, a flexible connection extending from the other end of the reciprocating saw-blade to an overweighted bell-crank lever

pivotaly supported on the lay, the bell-crank lever, a stop for the lever and a stop-rod connected with the stop mechanism and provided 45 with a shoulder, as described.

3. In a warp stop-motion for looms, the combination with the stop-rod d^{10} and the lay, of the fixed saw-blades $d' d'$, the saw-blade d , means for reciprocating the saw-blade d in 50 one direction, the lever d^7 , the overweighted pawl d^8 , the stop d^9 on the sword, detector-plates supported on the warp-threads, and the flexible connection between the lever d^7 and the saw-blade d ; whereby on the breaking 55 of a warp-thread the pawl engages with the stop-rod to stop the loom, as described.

4. In a warp stop-motion for looms, the fixed saw-blades, a reciprocating saw-blade, detector-plates, an overweighted pawl pivotally 60 secured to a part of the lay, the lay, a tension-spring, flexible connection between the spring and one end of the reciprocating saw-blade, flexible connections between the other 65 end of the reciprocating saw-blade and the pawl, and a stop-rod; whereby on the breaking of a warp-thread the pawl engages with the stop-rod to stop the loom, as described.

5. In a warp stop-motion, the combination with the lay, the loom stop mechanism, the 70 reciprocating member, the fixed member, and the detectors, of the overweighted pawl d^8 , the lever d^7 , and the stop d^9 , supported on the lay, and a flexible connection between the lever d^7 and the reciprocating member, 75 whereby the pawl is controlled, as described.

In testimony whereof I have signed my name to this specification in the presence of two subscribing witnesses.

HENRY A. OWEN.
